Iino

[11] Patent Number: Des. 375,294

[45] Date of Patent: **Nov. 5, 1996

[54] ELECTRONIC COMPUTER

94 06 224 1/1995 Germany
94 06 894 3/1995 Germany

[75] Inventor: Masaaki Iino, Saitama, Japan

[73] Assignee: Kabushiki Kaisha Toshiba, Kawasaki,
Japan

[**] Term: 14 Years

[21] Appl. No.: 41,814

[22] Filed: Jul. 25, 1995

[30] Foreign Application Priority Data

Feb. 2, 1995 [JP] Japan 7-2198
